UNITED STATES PATENT OFFICE.

RALPH H. DICK AND CARL F. WOLTERS, OF MARIETTA, OHIO, ASSIGNEES TO THE SAFE-CABINET COMPANY, OF MARIETTA, OHIO, A CORPORATION OF OHIO.

HEAT-RESISTING CABINET.

1,342,204.

Specification of Letters Patent.

Patented June 1, 1920.

Application filed February 27, 1918. Serial No. 219,526.

To all whom it may concern:

Be it known that we, RALPH H. DICK and CARL F. WOLTERS, both citizens of the United States, and residents of Marietta, Washington county, Ohio, have invented a new and useful Improvement in Heat-Resisting Cabinets, of which the following is a specification.

Our invention relates to cabinets or light weight safes intended for use as containers for valuable papers, documents, records or other articles, and our object has been to devise a construction which would combine with absence of great weight, elements to resist the entrance of heat to the interior, a strength and rigidity of construction which will prevent buckling under high temperatures or injury to the cabinet in the event of a fall or rough handling of any kind, together with marked simplicity and economy in the methods of construction employed.

In the many known forms of heavy iron safes disclosed in the art, there are examples in which between a thick outer wall and a lighter inner wall, a plastic mass of material containing enough water or other liquid to permit of a free flow, has been poured for the purpose of providing an element to delay the entrance of heat to the interior of the safe, and also to permit of the production of vapor or steam under high temperatures to moisten the contents and prevent their destruction by the heat. To this construction there are several objections. The heavy iron walls necessarily are of excessive weight which is always an objection for many reasons, and in addition are excellent conductors of heat.

The free water in the plastic filler poured into the space between the heavy outer and lighter inner walls is not bound or permanently fixed in the mass and therefore is certain to cause corrosion of the walls. It also dries out with age leaving cracks in the filler. It is obvious that when excessive heat reaches a heavy iron wall in proximity to such a crack that the heat will very quickly reach the interior of the safe. It is also impossible to be certain at any time as to the percentage

of water in such a filler. To make such a mass pourable there is an excess required beyond that required to make it a good heat insulator, but the conditions as to temperature and atmospheric moisture in the place where such a safe is located have a definite effect on the filling which can not be ascertained without tearing down the safe.

As is well known in the trade and to the public, this excess of moisture is also a menace when such a safe is new, for the reason that if the doors are kept closed for any length of time, "sweating"—as it is termed—will occur and the moisture will then pass to the interior of the safe causing the contents to become mildewed or otherwise damaged.

Another advantage arising out of forming the heat insulating lining outside of the casing walls, lies in the fact, that after the molded lining is removed from the mold, it can be inspected, and if there are any air holes or defects of any kind, caused by lumps in the mixture or the presence of any undissolved substances, they may be remedied before the lining is positioned in the casing.

In our invention herewith, these objections are overcome, as the heat insulation extends practically from the point where the excessive heat is located to the interior of the cabinet, and in addition contains only a predetermined amount of chemically bound water which remains bound until it is needed, when it is released by the high temperature.

Our present invention is superior to the double walled sheet metal cabinets in which heat insulating materials are placed between the said walls, in that our heat insulation is one integral member with no joints, seams or openings of any kind, cast in a mold to fit perfectly, its outer shell of sheet metal, and pre-dried at a fixed temperature, so that the exact amount of moisture best calculated to provide heat insulation remains chemically bound in the said casting. In actual practice it has been very laborious and expensive to construct these double walled cabinets with the heat insulating materials between the walls, because of the absolute necessity for the greatest care to avoid any crack or open-

ing of any kind in the insulation through which heat could pass to the interior. Of necessity some of these insulating materials are more or less brittle and therefore edges 5 or corners are liable to be chipped off in handling or fitting the insulation or in shaping it to fill in the corners and bends of the sheet metal walls. There is frequently much time and labor involved also in beveling, 10 shaping and fitting the said insulation. It is obvious that a weak spot will exist whenever any kind of an opening or break occurs in the insulating material.

A greater structural strength and rigidity 15 of construction is also found in this invention because of the reinforcement we provide in the cast insulation of our structure.

In the drawings herewith:—

Figure 1 is a perspective view of the 20 molded heat insulation lining of the structure.

Fig. 2 is a horizontal sectional view of the cabinet without doors.

Fig. 3 is a fragmentary vertical sectional 25 view of the upper part of the cabinet.

Fig. 4 is a fragmentary vertical sectional view of the lower part of the cabinet.

In the drawings, the reference numeral 10 indicates the sheet metal outer walls of 30 the structure, 11—11 being the side walls, 12 the back wall, 13 the top wall and 14 the bottom wall. These may be made in the usual manner and in any desired form or size and preferably are constructed to form 35 the top, bottom and side walls, with the back wall omitted to permit of the positioning of the cast insulation 15, after which the back wall may be placed in position and secured in any desired way, such as welded 40 for instance. As is obvious any one of the walls could be omitted for this purpose and the cast insulation could be positioned through the opening.

The heat insulating lining 15, may be 45 made of any material which can be mixed with water so that it can be molded to the desired form. Among other substances we have found practical a mixture of gypsum and a small proportion of saw dust or other 50 suitable material to give a needed elasticity and decrease the frangibility of the structure.

This mixture is poured into a mold constructed to follow precisely the form of the 55 inner sides of the outer steel walls. When it has set, the molded insulation lining is removed from the mold. On account of the quantity of water used to make a mixture which could be poured into the mold, this 60 cast lining now contains a superfluous amount of free moisture which if it were allowed to remain might cause corrosion of the metal outside walls, and in addition an unnecessary weight is caused thereby. The

cast therefore is placed in a drying room 65 in which a fixed temperature is maintained and with the aid of a blower apparatus, the free water is abstracted and only the chemically bound water is retained. This is sufficient when the completed cabinet is subjected to high temperatures, to escape in the 70 form of a vapor or steam into the interior of the cabinet where it will moisten the contents and aid in preserving them.

To reinforce the cast lining and give it 75 a strength that will prevent its breaking down under great heat, we insert in the mold before the mixture is poured, a sheet of mesh wire 16 which serves to hold the casting together at all times. In our tests 80 and experiments we have found that even when a very high temperature has calcined the material to almost a friable point, this reinforcement holds the casting in an integral unit.

In the corners of the cabinet and along the edges of the corners, where the greatest amount of heat is apt to make its way to the interior we form in the casting an increased thickness of the material as indicated at 17. 90

After the casting has been dried to the pre-determined point, the sheet metal casing is slipped on over the casting, the wall omitted to permit of the positioning, is secured in place and the front door or doors 95 are swung on the hinges.

If desired, inner walls or linings may be put in but this is optional as the casting itself has a fine finish and could be painted or stained and grooved to receive shelves 100 or other interior fittings.

We claim:—

1. A fire-heat resisting document-preserving cabinet or safe comprising an inner independent integral body including fixed walls 105 composed of a set composition containing chemically bound water or moisture, and an outer shell of sheet metal inclosing said integral body and independent thereof, said body being practically devoid, through artificial elimination, of free water and adapted under high temperature as in case of fire to release said chemically bound water in the form of vapor, said outer shell being operative in such case to prevent the exterior 115 escape of said released vapor and said structure being adapted to permit the escape to the interior from said walls of such released vapor into contact with the contents of the cabinet.

2. A fire-heat resisting document-preserving cabinet or safe comprising an outer shell of sheet metal, an inner integral body structurally independent of said outer shell and including fixed side, top, bottom and back 125 walls, said body being composed of a set composition containing chemically bound water or moisture and being practically de-

void, through artificial elimination, of free water and adapted under high temperature as in case of fire to release said chemically bound water in the form of vapor, said outer shell being operative in such case to prevent the exterior escape of said released vapor and said structure being adapted to permit the escape to the interior from said walls

of such released vapor into contact with the contents of the cabinet.
